UNITED STATES PATENT OFFICE.

SAMUEL J. TURNER, OF CHICAGO, ILLINOIS.

DESIGN FOR A CORNER-POST FOR BEDSTEADS.

SPECIFICATION forming part of Design No. 30,344, dated March 14, 1899.

Application filed February 4, 1899. Serial No. 704,586. Term of patent 7 years.

To all whom it may concern:

Be it known that I, SAMUEL J. TURNER, a citizen of the United States of America, residing at Chicago, in the county of Cook and State of Illinois, have invented a certain new and original Design for Corner-Posts for Bedsteads, of which the following is a specification.

My design is illustrated in the drawings by means of two views, the first of which (marked Figure 1) is an edge elevation, and the second of which (marked Fig. 2) is a side elevation.

The post here shown contains a main portion A, comparatively thin and broad, upon

one side of which are a series of lateral projections or bosses a.

The characteristic features of this design are comprised in a corner-post for bedsteads having the comparatively thin and broad main portion A provided with the lateral projections or bosses a.

I claim as new and desire to secure by Letters Patent—

The design for a corner-post for bedsteads, as herein shown and described.

SAMUEL J. TURNER.
